UNITED STATES PATENT OFFICE.

SHERMAN HOYT, OF BROOKLYN, NEW YORK.

PORTABLE BOWLING-ALLEY.

SPECIFICATION forming part of Letters Patent No. 469,249, dated February 23, 1892.

Application filed December 2, 1891. Serial No. 413,754. (No model.)

To all whom it may concern:

Be it known that I, SHERMAN HOYT, a citizen of the United States, and a resident of Brooklyn, in the county of Kings and State 5 of New York, have invented certain new and useful Improvements in Portable Bowling-Alleys, of which the following is a specification.

My invention relates to portable games, 10 which may be used in an ordinary dwelling without especial room or arrangement thereof; and it consists of a portable bowling-alley, which is made of size convenient and may be placed upon an ordinary table and used by 15 one or more persons, and when not in use may be removed and stowed away, like any other piece of furniture, as herein described.

In the accompanying drawings, Figure 1 is a longitudinal section of the bowling-alley, 20 showing the pins in position and a ball ready to be propelled to throw them into the pit. Fig. 2 is a plan view of the bowling-alley. Fig. 3 is a transverse section of the same.

My bowling-alley consists of a bed-plate *a*, 25 of hard wood or other suitable material, being cut out near its end to form a pit and at both sides at *a*² to form the usual gutters. To the sides and the end, respectively, of this bed-plate *a* are glued or otherwise firmly secured 30 the side plates *b* and the end plate *b'*, and each of these is preferably provided with a spirit-level *l*, mounted exactly parallel with the upper surface of the bed-plate *a*. In front of the pit *p* are the usual spots for the ten-pins, 35 marked or inlaid into the bed-plate *a*, and the pins *p'* and balls *r* are preferably made in the proportions used in ordinary bowling-alleys. At the end of the alley is mounted a swinging recoil-board *d*, provided in front with suitable 40 cushions and suspended above from pins or hinges *h*, mounted in the side boards *b b*. The entire apparatus is supported by three screw-legs *s*, which, in combination with the spirit-level *l*, will allow an exact horizontal adjustment 45 of the portable bowling-alley upon an ordinary table, this adjustment being essential in this case for accurate work, (the ordinary floor and table-top being seldom level enough to insure good play.) The bed-plate 50 *a* may also be hollowed out on top and filled

with cement or other suitable material capable of carrying a level surface which is not liable to warp or bend, and any other number of pins may be employed.

In using the portable bowling-alley it is first 55 adjusted upon the top of a parlor or dining table by the aid of the screw-legs *s* and spirit-levels *l* till the bed-plate is rendered perfectly horizontal. The pins having been set in position, a ball is placed upon the front end of 60 the alley-bed near its middle and then actuated by a player by preferably snapping at it and striking it with a finger. I do not confine myself to this especial mode of propelling the ball, but any other suitable tool or mechanical device may be employed for this purpose. 65

In cheaper grades of my toy the spirit-levels may be omitted, as a level plane can be established by the aid of the screw-legs without the spirit-levels after short experience with the 70 balls.

Having thus described my invention, what I claim, and desire to secure by Letters Patent, is—

1. In a portable bowling-alley, the combination of the bed-plate *a*, provided with troughs *a*², pit *p*, and adjustable screw-legs *s* and having attached to it the side boards *b b* and end board *b'*, carrying spirit-levels *l*, with the swinging recoil-board and the pins and balls, as and 75 for the purposes herein shown and described. 80

2. In a portable bowling-alley, the combination of the bed-plate *a*, having attached to it the side boards *b b* and end board *b'*, and the screw-legs *s*, with a swinging recoil-board *d*, as 85 and for the purposes herein shown and set forth.

3. In a portable bowling-alley, the combination of the bed-plate *a*, having secured to it the side boards *b b* and end board *b'*, with the 90 swinging recoil-board *d*, as herein shown and described.

Signed at New York, in the county of New York and State of New York, this the 1st day of December, A. D. 1891.

SHERMAN HOYT.
